CLAIM

USPC **D9/516**; D9/434; D9/544

The ornamental design for a wine bottle, as shown and described.

(58) **Field of Classification Search**

DESCRIPTION

USPC D7/300, 500, 507, 509, 523, 590, 598,

FIG. 1 is a front perspective view of a wine bottle.
FIG. 2 is a front elevational view of the wine bottle shown in FIG. 1. The rear, left, and right sides being identical to the front.

D7/602, 619.1; D9/434, 443, 444, 453,

FIG. 3 is a top plan view of the wine bottle shown in FIG. 1; and,

D9/454, 500, 502, 503, 516, 520, 529,

FIG. 4 is an enlarged detail view of area 4 called-out in FIG. 2.

D9/530, 539, 540, 544–546, 549, 550,

The dot-dash-dot broken line in FIGS. 1 and 3 depicts the boundary of the claim and forms no part thereof. The bolded dash-dot broken line encircling the area of the detail in FIG. 2 and surrounding FIG. 4 denotes the boundary of the enlarged detail and forms no part of the claimed design. All other broken lines depict portions of the wine bottle that

D9/558, 715, 719, 435, 436, 439, 440;

form no part of the claimed design. All surfaces not shown form no part of the claimed design.

D3/202

CPC B65D 41/42; B65D 1/0246; B65D 1/0223;
B65D 21/022; B65D 2501/0036; B65D
1/10; B65D 1/02
